UNITED STATES PATENT OFFICE.

WILLIAM HARVEY SPOWERS, OF ESSEX FELLS, NEW JERSEY.

DESIGN FOR A TEXTILE FABRIC.

Application filed May 8, 1928. Serial No. 26,607. Term of patent 3½ years.

To all whom it may concern:

Be it known that I, WILLIAM HARVEY SPOWERS, a citizen of the United States, residing at Essex Fells, in the county of Essex and State of New Jersey, have invented a new, original, and ornamental Design for Textile Fabric, of which the following is a specification, reference being had to the accompanying drawing, forming part thereof.

The figure is a top plan view of a piece of textile fabric showing my design, the representative illustration included in the broken line rectangle being repeated in diagonally offset relation, as indicated by the diagonal broken lines, throughout the length and width thereof.

I claim:—

The ornamental design for textile fabric, as shown and described.

WM. H. SPOWERS.
